Apollo Richmond, of Providence, R.I.-

assignor to

A. G. Barstow, & Co

Letter Patent No. 424. Dated, Nov. 18, 1851.

The schedule referred to in these Letters Patent, making part of the same.

To all Persons to whom these Presents shall come:

Be it

Known that I, Apollo Richmond of Providence, in the County of Providence & state of Rhode Island, have produced a new & original design for the front ends & top plates of a parlor-stove and I hereby declare that the said new design is fully described & represented in the following specification & accompanying drawings to which reference is hereinafter made.

The figures of the accompanying plate of drawings represent my new design.

In Plate 1, Fig. 1, is an elevation of the front plate. In Plate 2, Fig. 2, is an elevation of the end plate. In Plate 3, fig. 3, is a top view of the top plate. In Plate 4, fig. 4, is a section of the front plate taken in the plane of the line A, B, Fig. 1, pl. 1 & Fig. 5, is a section of the top plate taken in the plane of the line B C, Fig. 3 pl. 3.

In the front plate, the doors are surrounded

by the mouldings a, a, a &c, of the shape shown in the drawings, and have the sunken panels b, b, b, leaving the centre of the door of the shape, shown in fig 1, this part of the door is ornamented with the raised curved figures c, c &c, - d, d &c, and the spear heads e, e.

Above the doors are two panels ornamented in the same manner as the doors. On the sides of this plate are the semicircular mouldings or pilasters f, f, from which, across the top run the mouldings g, g &c. Between the mouldings f, f, & the central part of the plate on which are the doors & panels above described are the curved figures h, h - h h. The bottom of the plate is ornamented with the raised scroll work i, i, i, &c.

The end plate is ornamented on the top, bottom & sides, with the mouldings g, g, scroll work i, i and pilasters f, f, &c, this plate having in the centre, two panels, one above the other, with mouldings, raised curved work &c, precisely like those in the front plate.

The top plate is of the shape shown in Fig. 3, pl. 3, and has around its sides the mouldings k, k, k, &c, and the head work l, l, &c, inclosed by the raised figures m, m.

The cover has on it, the curved pieces and spear heads j, j, and n, n, &c, and the figures o, o, this cover is set in a ring formed by the mouldings p, p &c. The top part of this plate is also ornamented with the raised crescent shaped panels q, q, on which is the scroll work r, r, &c.

Having thus described my new design, I shall state my claim, as follows: -

What I claim as my production & design to have secured to me by Letter, Patent, is the new design

Ms. 425

consisting of, the mouldings of panel & ornamental configurations, herein above described & represented in the drawings, respectively for the top, front & end plates of a parlor ~~stone~~.
